H. J. LESLIE ET AL

RING COMPRESSING TOOL

Filed Dec. 22, 1924

UNITED STATES PATENT OFFICE.

HARRY J. LESLIE AND EARL RABY, OF ST. JOSEPH, MISSOURI.

RING-COMPRESSING TOOL.

Application filed December 22, 1924. Serial No. 757,501.

The present invention relates to ring-compressing devices, with particular reference to appliances for use in retaining piston rings compressed within the grooves of the piston, during the operation of inserting the piston and ring assembly into the bore of the cylinder.

Accordingly, it is the object of the present invention to devise a practical, simple and easily operated tool for compressing and retaining the rings within the piston grooves and adapted to be maintained latched in this spring compressing relation without attention on the part of the operator for this purpose, so that the hands of the operator may, if desired, be temporarily free for other operations incidental to the assembly of the pistons within the cylinders.

It is further sought to provide a device of this character which will be adjustable to a certain extent for use with piston rings of various sizes, and adapted to exert a practically uniform pressure all around the rings, and to facilitate the insertion of the piston and ring assembly in a direction coinciding substantially with the axis of the cylinder.

In carrying out the invention in practice, we make use of a spring metal construction comprising ring engaging segments which are adjustable for different sizes of rings, and provided with a compressible handle for actuating the segments into ring-clamping position, this handle being provided with a keeper element movable along the handle for either releasing or compressing the same and retaining the parts in their ring-clamping position.

With the foregoing general objects in view, the invention will now be described by reference to the accompanying drawing, illustrating one form of construction which we have devised for embodying the proposed improvements, after which those features deemed to be novel will be particularly set forth and claimed.

In the drawing—

Figure 1 is a plan view of a tool constructed in accordance with the present invention, and illustrated in expanded position ready for application to a piston;

Figure 2 is a side or edge view of the same;

Figure 3 is a plan view illustrating the device applied to the piston in ring-clamping position;

Figure 4 is a side view of the parts illustrated in Figure 3, and illustrating the op-

eration of inserting the piston ring assembly within a cylinder;

Figure 5 is a fragmentary detail view, showing one of the spring-clamping segments of the tool before the guide loops have been secured thereto; and

Figure 6 is a detail section taken on the line VI—VI of Figure 1.

Referring now to the drawing in detail, this illustrates the improved appliance as made from a band of spring metal which has been suitably shaped to provide a handle portion 7 oppositely bowed as shown in Figures 1 and 3, and terminating in ring engaging and clamping segments 8, the free end portions of which are arranged in overlapping relation, as illustrated in the same views, in order to provide adjustments of the size of the tool for rings of different diameters.

One of the segments 8 terminates in a relatively short finger portion 8' which is doubled back upon the adjacent portion of said segment, and is secured thereto by means of a pair of spaced guide loops 9 of a size large enough to accommodate three thicknesses or plies of the metal, since these loops are designed for slidingly accommo-

dating the free end portion of the other ring-clamping segment 8. Normally, the finger extension 8' projects at an angle to the adjacent portion of the attached segment 8, and is of a slightly less pronounced curvature, as shown in Figure 5, so that when secured by the loops 9 to the segment 8, in en-

gagement therewith throughout the length of said extension 8', the end portion of the latter which is attached to said extension is subjected to a slight straightening tendency by the action of the extension 8', as will be readily understood.

Since the curvature of both of the ring-engaging segments 8 is normally the same, the projection of the free end of one of them through the guide loops 9 of course causes the same to be embraced with a friction grip, thereby holding the connected parts of the ring-engaging segments against any casual displacement or alteration of its adjustment except at such times as this adjustment is purposely altered by the workman.

One of the ring-clamping segments may be graduated, if desired, as indicated at 10, to denote the different sizes to which the tool may be adjusted for a given range of ring sizes.

The handle portion of the tool is provided with an interior spring member 12, bowed

in the same manner as the handle but in opposite direction, with the end portions of the member 12 secured, as by welding, to the opposite sides of the handle 7. This 5 leaves the middle portion of the spring member 12 presented opposite the gap between the ends of the ring-clamping segments 8 at the points where they are attached to the handle 7, thus adapting this midportion of 10 the member 12 to engage the portions of the rings 14 which may not be engaged by the segments 8.

Slidably mounted upon the handle portion 7 is a loop or keeper member 15 formed 15 with finger-engaging extensions 15' and having a cross bar 16 extending through the handle and adapted, by engagement with the extreme end thereof, to prevent any complete disengagement of the member 15 from 20 the handle. It is apparent that by moving the loop or keeper 15 out to the extreme end of the handle as illustrated in Figures 1 and 2, the spring tension of the tool is released, as required for removing the tool from 25 clamping engagement with the piston; whereas, by forcing the loop or keeper 15 to the opposite end of the handle, as shown in Figures 3 and 4, the handle is compressed, thereby correspondingly compressing the 30 ring-clamping segments 8 into tightly clamped relation to the rings 14, as required for holding the latter compressed within the grooves of the piston, in the usual manner, preliminary to inserting the piston and ring 35 assembly within the bore 17 of the cylinder 18, as seen in Figure 4. Preferably, the under side of the handle 7 is undercut, as illustrated at 20 in Figures 2 and 4, so that the member 15 may be moved into handle-compressing position without any interference being offered by the cylinder head (see Figure 4).

It will thus be apparent that we have devised a practical, simple and very efficient 45 device for carrying out the proposed objects of the invention. In practice, it is common to locate the split piston rings 14 in staggered relation, that is with their butt joints at different points around the surface of the 50 cylinders, so that it quite often happens that one of these joints will come opposite the gap left between the segments 8 at the point where they are attached to the handle 7. If the butt ends of the rings come at 55 this point, it is quite natural that they will prevent the ready insertion of the piston within the cylinder, on account of projecting outside the piston groove; but in the present construction the tool will prevent any projection of the ring outside the groove, since the spring member 12 will engage the ring 60 14 at this point and will operate automatically, on compression of the handle 7 by the movement of the loop or keeper member 15, to engage and force the ring within the

groove and retain it in said position during the operation of inserting the piston within the cylinder. It will be evident also that with such a construction the pressure exerted upon the ring will be substantially uniform 70 entirely around the cylinder, and that the loop member 15 will be retained automatically, by the spring tension of the tool, in the position shown in Figure 3 without any further attention from the operator, whose 75 hands are thus left free for other manipulations which may be required in this work. In this connection, it may be further explained that the loops 9 prevent any tendency of the ring-clamping segments to follow along with the piston into the cylinder bore, and since these loops come opposite the member 15 at the other side of the cylinder, the piston assembly is properly aligned with the axis of the cylinder bore, thus 85 facilitating the movement of the piston in a direct line with the cylinder axis.

The improved device has the further advantages of being of an extremely light and compact character, with great flexibility 90 which promotes the ease of its operation, and on account of the absence of any hinge joints, or adjusting clamps or screws, there is practically nothing to get out of order in the device, and the cost of manufacture of 95 the device is correspondingly low. It is moreover evident by virtue of the character of the material used in its manufacture, and its simplicity of construction, the durability 100 of the improved device is correspondingly great.

While we have illustrated what we now regard as the preferred form of construction, we desire to reserve all rights to make whatever changes or modifications may fairly 105 fall within the scope of the appended claims.

What we claim is:

1. A ring-compressing tool comprising a ring-engaging portion composed of spring 110 metal segments having adjustable overlapping end portions, one of said end portions having guiding means for slidably engaging the other end portion and exerting a straightening action thereon, a handle portion 115 connected with said segments and operative to contract the latter into spring-compressing relation, and a device mounted slidably on said handle portion and cooperating therewith to retain said segments in ring-clamping relation.

2. A ring-compressing tool comprising a single piece of spring metal forming a handle portion and a pair of ring-compressing segments having adjustable overlapping end portions, a spring element within said handle portion for engagement with the ring intermediate said segments, and a device carried by said handle portion for retaining the parts in ring-clamping relation.

3. A ring-compressing tool comprising a single piece of spring metal forming a handle portion and a pair of ring-compressing segments having adjustable overlapping end portions, a band of spring metal within said handle portion and having its ends secured to the opposite sides of the handle portions for presenting the intermediate portion of the band in position for engagement with the ring intermediate said segments, and a device carried by said handle portion for retaining the parts in ring-clamping relation.
- 10 4. A ring-compressing tool comprising a

single piece of spring metal forming a handle portion and a pair of ring-compressing segments having adjustable overlapping end portions, a spring element within said handle portion for engagement with the ring intermediate said segments, and a loop or keeper device slidingly carried by said handle portion for retaining the parts contracted into ring-clamping relation.

In witness whereof we hereunto affix our signatures.

HARRY J. LESLIE.
EARL RABY.
